UNITED STATES PATENT OFFICE.

WILLIAM BLIESNER, OF ST. LOUIS, MISSOURI.

IMPROVEMENT IN VAPOR-BURNERS.

Specification forming part of Letters Patent No. 98,842, dated January 18, 1870.

Be it known that I, WILLIAM BLIESNER, of St. Louis, in the county of St. Louis and State of Missouri, have invented an Improved Self-Acting Oil-Vapor-Generating Burner as a new article of manufacture; and I do hereby declare that the following is a full, clear, and exact description of the construction and operation of the same, reference being had to the annexed drawings, making a part of this specification, in which—

Figure 1 is a vertical section of the burner in combination with the lamp. Fig. 2 is a view of the burner-bottom of the valve, which is intended to close the upper part of the oil-reservoir. Fig. 3 is a vertical section of the burner, with an extra cap intended to form a flat flame. Fig. 4 is a front elevation of the burner, with an extra cap intended to form a tubular flame. Fig. 5 shows the upper part of the burner, with the cap exhibited in Fig. 4.

My improvement appertains to that class of burners where gas is generated from oil, on a small scale, and in proportion to the quantity consumed by heating and vaporizing the oil, just before it escapes from the conducting-pipe.

The oil passes through the tube D to the horizontal capillary tube or generator C¹, which is kept in a heated state, when the lamp is burning, by the immediate contact with the bunchy knot or heater C². Passing through the generator C¹, the oil is vaporized, and the vapor, descending through the vertical capillary tube, escapes from a small opening, in gas-form, and, passing upward through the cylindrical mixing-chamber C³, is mixed with the atmospheric air, which enters at the base of the mixing-tube, and arrives at the top of the burner in a suitable state to generate a clear and brilliant gas-flame.

The knot C² is heated by two small flames, which emanate from the two lateral heating-orifices C⁴ in the gas-tube C³, immediately below the top end of the same.

The particularity of my invention consists in the arrangement of the horizontal gas-generating capillary tube C¹, in immediate contact with the heating-knot C², near the top of the burner, and in immediate vicinity of the heating-orifices C⁴, and near the principal flame, and in the arrangement of the vertical capillary tube in immediate contact with the gas-burner C³, whereby the heating-process is greatly facilitated.

The form of the principal flame or light depends on the application of the caps of different form: Fig. 3 for the flat form, Fig. 1 for star form, and Fig. 4 for tubular form. All these caps must be so constructed as to leave the heating-orifices C⁴ free.

The upper part of the oil-reservoir may be closed by a valve, B, as exhibited in Fig. 2, which is closed by covering the lower part with a thin membrane, which is provided with small incisures, a little distant from the inner end of the tubular air-channel b. This valve will admit the air to the reservoir, when necessary, but it will prevent the escape of the oil.

When the lamp shall be lighted, the check-valve E is opened. A portion of the oil flows out and gathers in the pan, which is attached to the lower end of the burner. There, being directly lighted, it warms the apparatus to a vaporizing degree, and from that moment the oil escapes in gas form.

What I claim as my invention, and desire to secure by Letters Patent, is—

The vapor-burner C, provided with horizontal and vertical capillary gas-generating tube C¹, heating-knot C², heating-orifices C⁴, and mixing-chamber C³, all arranged for joint operation, substantially as herein described, and for the purposes set forth.

WILLIAM BLIESNER.
